[57] ABSTRACT

Choke valves are provided in association with submersible pumps employed in oil wells or the like to prevent the flow of well fluid toward the well head when the pump is not operating. Differential pressure across the pump is employed to open the valve, and the valve closes automatically when the pump is de-energized. Bottom-hole pressure merely closes the valve more tightly. The pump may be located above or below the valve, and several different choke configurations with different modes of valve operation are disclosed. The storm chokes can be opened by fluid pressure applied from the earth's surface in order to permit "killing the well" or flushing sand from the choke.

FIG. 3

STORM CHOKE APPARATUS FOR SUBMERGIBLE PUMPS

BACKGROUND OF THE INVENTION

This invention relates to storm chokes and is more particularly concerned with well valves which open automatically when a submersible pump is actuated but which otherwise remain closed.

It is common practice to provide an oil well or the like with a device known as a storm choke for blocking the path by which the well fluid may flow to the earth's surface when such flow is not desired. For example, it is well known to provide well safety or blowout control valves which may be operated by a wire line, by hydraulic or pneumatic pressure transmitted from the surface, or in response to well flow rate or pressure parameters to shut off the flow of well fluid to the surface when such flow would be undesirable or dangerous. See, for example, U.S. Pat. Nos. 3,265,134; 3,035,641; 3,284,174; 3,090,433; 3,568,768; 3,273,606; 2,962,099; and 3,477,507. Devices of this type tend to be complicated, expensive, unwieldy, and/or unreliable. It is known to employ various types of valves in conjunction with pumps, as shown, for example, in U.S. Pat. Nos. 1,775,480; 2,722,395; 3,610,268; and 1,329,704, but such devices are not suited for use as effective storm chokes in conjunction with submersible pumps.

SUMMARY OF THE INVENTION

It is accordingly a principal object of the present invention to provide improved storm choke apparatus or the like.

Another object of the invention is to provide storm chokes which open automatically in response to the operation of an associated submersible pump.

A further object of the invention is to provide storm chokes which are attached to or part of the submerged inlet or outlet housing of a submersible pump and in which all of the choke parts are adjacent to the pump and not dependent upon connections to distant operators.

Yet another object of the invention is to provide storm chokes of the foregoing type which are normally closed by biasing springs and which remain firmly closed under bottom-hole pressure, but which are readily opened in response to differential pumping pressure.

Briefly stated, the storm chokes of the invention employ valves associated with submersible pumps, which may be located above the valve or below the valve. When the pump is actuated, the differential pressure across the pump is applied to a valve operator which opens the valve. Reciprocating piston operators are preferred, and in one embodiment the moving valve member itself constitutes the operator piston. In other embodiments the pump output pressure is applied to one side of the operator piston through passages in a wall of the choke housing or in the pump shaft, the opposite side of the piston being exposed to the pump input pressure.

BRIEF DESCRIPTION OF THE DRAWINGS

The invention will be further described in conjunction with the accompanying drawings, which illustrate preferred and exemplary embodiments, and wherein:

FIG. 1 is a contracted longitudinal sectional view of a first embodiment of the invention;

FIG. 2 is a longitudinal sectional view of a second embodiment of the invention; and

FIG. 3 is a longitudinal sectional view of a third embodiment of the invention.

DETAILED DESCRIPTION OF THE INVENTION

Referring to the drawings, and initially to FIG. 1 10 thereof, storm choke apparatus of the invention comprises an elongated tubular housing 10 of generally cylindrical shape. The lower end of the housing is provided with an opening 12 circumscribed by a valve seat or sealing washer 14 engaged by a disc-like main valve member 16. Valve member 16 is supported upon a shaft 18 which is reciprocatively mounted in a bearing sleeve 20 formed at the lower end of a chamber 22, which is supported in the housing 10 by means of a spider 24. When the valve member 16 is closed against the seat 14, the space within the housing 10 at one side of the valve member is isolated from the space at the opposite side of the valve member. Thus, if the housing 10 is submerged in the fluid of a well, for example, the fluid is prevented from entering the housing when valve member 16 is closed. The valve member 16 is normally biased closed by a coil spring 26 which surrounds rod 18 and applies a force between an end of bearing sleeve 20 and a piston 28 fixed to shaft 18. The piston is cup-shaped and is arranged to reciprocate within chamber 22, a seal to the chamber wall being provided by means of an O-ring 30. A further shaft 32 is supported for reciprocation through shaft 18 and has one end attached to an inverted cup-shaped piston 34 supported for reciprocation within piston 28 and provided with an O-ring seal 36 between the pistons. A coil spring 38 normally biases piston 34 away from piston 28. The opposite end of shaft 32 is provided with a priming valve element 40 having an O-ring 42 which seals against the bottom of valve member 16. One or more passages 44 extend through the valve member 16 and are opened to the space below valve member 16 when valve element 40 is opened, shaft 32 being grooved near its lower end to provide paths for fluid to enter the passages 44.

Located in housing 10 above the chamber 22 is a submersible fluid pump generally designated by reference numeral 46. The pump is preferably of the centrifugal type, comprising a central pump shaft 48 on which impellers 50 are mounted. The impellers cooperate with diffusers 52 mounted on the housing 10. The pump shaft 48 is supported upon bearing spiders 24 and 54. The upper end of the pump shaft may be splined for coupling to a similar shaft section of an additional (or several additional) pump stages. The upper end of the pump shaft (or the uppermost section thereof) may be driven by an electric motor (not shown) located in the housing 10 or in a housing fixed to the uppermost stage of the pump. Pumps of the type illustrated are disclosed, for example, in U.S. Pat. Nos. 2,775,945; 2,270,666; and 2,236,887. An O-ring seal 56 is provided at the bottom of the pump shaft to prevent leakage into the chamber 22. The output side of pump 46 is connected to chamber 22 above piston 34 by a longitudinal passage 58 through the pump shaft, a transverse admission port being provided at 60. The entire pump installation, including the choke, pump stages, motor, and auxiliary apparatus may be suspended in a well

from a cable, as taught, for example, in Pat. Nos. 3,672,795; 3,468,258; and 3,411,454, and the fluid discharge of the pump may flow to the surface through the well casing or a liner, as disclosed in those patents, or through a conventional tubing string. This type of installation may also be used in the other embodiments described hereinafter.

In operation, it is assumed that housing 10 is submerged in and contains well fluid. When the pump 46 is actuated, the output pressure is applied through passage 58 to the upper side of piston 34, moving this piston downwardly in piston 28 and moving valve element 40 so as to expose the passages 44 to the well fluid below valve member 16. The slight amount of fluid displaced by movement of piston 34 in piston 28 passes between shaft 32 and shaft 18 (which fit loosely enough or are provided with longitudinal grooves). Only very slight movement of piston 34 is required to open valve element 40 and to permit well fluid to enter the passages 44. Thus primed, the pump continues to operate, driving piston 34 downwardly into engagement with piston 28. Piston 28 then moves downwardly to open the main valve member 16 and provide full flow through the main valve and through housing 10 to the pump discharge head. Fluid trapped in chamber 22 below piston 28 is vented by means of a vent 62, which is branched to provide a recirculatory path indicated by arrow A. The recirculation tends to reduce the upward force on piston 28 which would otherwise be exerted by well fluid rushing into the chamber 22 by means of the vent.

As long as the pump is operating, the differential pressure across the pump is sufficient to maintain the main valve 16 open against the bias spring 26, the top of pistons 28 and 34 being subjected to the output pressure and the bottom of the pistons being exposed to the input pressure of the pump. Enough stages of impeller-diffuser units are provided below port 60 to ensure that the differential pressure exerted upon the valve operator in chamber 22 is sufficient to open the main valve 16 and to maintain the valve open during pumping. When the pump is de-energized, however, the return springs 26 and 38 move pistons 28 and 34 upwardly, closing valve member 16 against its seat and closing valve element 40 against valve member 16. Bottom-hole pressure exerted against lower surfaces of the valve structure merely closes the valve more tightly. However, valve member 16 may be opened by fluid pressure applied to the top of the valve member from the earth's surface in order to "kill the well" or to flush sand from the vicinity of the valve member.

In order to avoid the need for the rotary seal 56 at the bottom of the pump shaft, the embodiment of FIG. 2 may be employed. This embodiment is generally similar to that of FIG. 1, as indicated by the reference characters employed, but communication between the chamber 22 and the output side of the pump 46 is provided by passages 64 and 66 formed in a transverse partition 68 and by a longitudinal passage 70 formed in the wall of the housing 10. Partition 68 has main flow passages 69. It is simpler to provide a long passage 70 in a long housing rather than a long passage 58 in a long pump shaft, as in FIG. 1. Passage 70 may be formed as a longitudinal groove in the inner surface of the side wall of the housing 10, the open side of the groove being covered by the outer surface of the diffusers 52 (only some of which are shown).

FIG. 3 illustrates an embodiment intended for use with a pump which is mounted below the storm choke, the pump being indicated diagrammatically at 116 and the storm choke housing being indicated at 118. The pump may be of the type shown in the aforesaid Pat. Nos. 2,270,666 and 2,775,945, for example, driven by an electric motor from below. Housing 118 and pump 116 are suspended in the well fluid as stated above, the pump having inlet ports exposed to the well fluid outside of housing 118. The upper portion of the housing is provided with a cylindrical head 120 having a depending wall 122 spaced inwardly from the side wall of housing 118 to provide an annular space 124 for reception of a cylindrical valve member 126. Chamber 124 above the valve member is vented to the outside of housing 118 by a passage 127. Valve member 126 is normally urged downwardly into engagement with a circular groove valve seat 128 by a series of coil springs 130. The side walls of the valve seat and the lower edges of valve member 126 preferably have mating tapers as shown. Valve seat 128 is formed in the top surface of a transverse partition 132 having a series of circumferentially spaced longitudinal passages 134 extending from space 136 to the valve seat region.

When the pump is not energized, valve member 126 is held closed by the return springs 130 and by the bottom-hole pressure exerted upon the top wall of the valve member, the area of the top wall exposed to the bottom-hole pressure through vent 127 being substantially greater than the area of the lower wall of the valve member 126 exposed to the bottom-hole pressure through passages 134. When the pump is operating, however, the output pressure in space 136 is transmitted through passages 134 to the bottom of valve member 126, the top of the valve member being exposed to the input pressure through passage 127, moving the valve member upwardly against the bias of springs 130 to open the valve and to permit full flow into the space 138.

Back flushing to kill the well or to remove sand or the like in the vicinity of valve member 126 and its valve seat may be provided by means of a normally closed poppet valve 140. The poppet valve controls passages 142 extending through the partition 132 and is normally closed by a return spring 144 and by the bottom-hole pressure. When it is desired to kill the well or to flush the storm choke, brine is pumped into the space 138 from above, and the pressure on the poppet valve 140 exerted through the passages 142 is sufficient to open the valve.

While preferred embodiments of the invention are shown and described, it will be apparent to those skilled in the art that changes can be made in these embodiments without departing from the principles and spirit of the invention, the scope of which is defined in the appended claims.

The invention claimed is:

1. Storm choke apparatus for use with submergible pump means, comprising a tubular housing associated with said pump means and adapted to be submerged in a fluid to be pumped therethrough, valve means supported upon said housing and having a movable valve member which, when in a closed position, isolates a space in said housing at one side of said member from a space at a different side of said member, with at least said different side of said valve member exposed to said fluid to be pumped, operating means coupled to said

valve member and responsive to differential pumping pressure across said pump means for moving said valve member to an open position for providing communication between said spaces, means coupled to said valve member for moving said valve member to a closed position in the absence of said differential pumping pressure, and means for maintaining said valve member closed irrespective of the pressure of said fluid at said different side of said valve member.

2. Apparatus in accordance with claim 1, wherein said operating means comprises piston means and means for subjecting opposite sides of said piston means to said differential pumping pressure.

3. Apparatus in accordance with claim 2, wherein said pump means is located in said housing at said one side of said valve member for pumping fluid away from said valve member, said piston means being located in a chamber at said one side of said valve member.

4. Apparatus in accordance with claim 3, wherein said pump means comprises rotary pump elements fixed to a shaft in said housing extending along the length thereof, said chamber being located between an end of said shaft and said valve member.

5. Apparatus in accordance with claim 4, wherein said chamber is connected to the output of said pump means by a passage extending through and along said shaft.

6. Apparatus in accordance with claim 4, wherein said chamber is connected to the output of said pump means by a passage extending along a wall of said housing.

7. Apparatus in accordance with claim 3, wherein said valve member has an operating rod connected to said piston means and extending into said chamber.

8. Apparatus in accordance with claim 3, wherein said valve means comprises a priming valve element which is movable to provide restricted communication between said spaces before movement of said valve member provides communication between said spaces.

9. Apparatus in accordance with claim 8, wherein said piston means includes a pair of relatively movable pistons for first opening said priming valve element and for then opening said valve member.

10. Apparatus in accordance with claim 8, wherein said valve member is supported upon a shaft movable into and out of said chamber, said valve element is supported upon a shaft supported upon the first mentioned shaft, and wherein said valve member has a passage therethrough controlled by said valve element.

11. Apparatus in accordance with claim 8, wherein

said valve member and said valve element are spring-biased to closed positions.

12. Apparatus in accordance with claim 3, wherein the input side of said pump means is connected to said chamber at one side of said piston means by a vent through a wall of said chamber, said vent having means for providing a recirculating path thereto to reduce the force upon said piston means by fluid entering the vent.

13. Apparatus in accordance with claim 1, wherein said means for moving said valve member to a closed position comprises a biasing spring.

14. Apparatus in accordance with claim 1, wherein said pump means is located at said different side of said valve member for applying the output pressure of said pump means directly to said different side of said valve member to move said valve member away from a cooperating valve seat.

15. Apparatus in accordance with claim 14, wherein said means for moving said valve member to said closed position comprises means for spring-biasing said valve member against its seat.

16. Apparatus in accordance with claim 15, wherein said means for maintaining said valve member closed comprises a surface of said valve member exposed to the pressure of said fluid to be pumped, said surface having greater area than the surface of the valve member exposed to said fluid at the opposite side.

17. Apparatus in accordance with claim 16, wherein said valve member is a cylinder having an end portion engaging said seat and wherein said seat is formed in a partition dividing said housing transversely and having passage means therethrough terminating at said seat.

18. Apparatus in accordance with claim 17, wherein said partition has a further passage therethrough internally of said valve member, said further passage being normally closed by a further valve member which may be opened against the bias of a spring by fluid pressure exerted upon said further valve member through said further passage from above said partition.

19. Apparatus in accordance with claim 1, further comprising means for providing communication between said spaces in response to fluid pressure exerted in said housing at said one side of said valve member.

20. Apparatus in accordance with claim 19 wherein the last-mentioned means comprises means for applying fluid pressure to said valve member at said one side to move said valve member to an open position.
